2 Sheets-Sheet 2

Technical drawing of a cylindrical component, likely a bearing housing or sleeve, showing internal and external dimensions. The drawing includes the following labeled features and dimensions:

- External Dimensions:**
  - Top outer diameter: 39
  - Bottom outer diameter: 35^a
  - Left outer diameter: 36
  - Right outer diameter: 37
  - Bottom outer diameter: 38
- Internal Bore Dimensions:**
  - Top bore diameter: 29^a
  - Bottom bore diameter: 27
  - Left bore diameter: 41
  - Right bore diameter: 43
  - Bottom bore diameter: 48
  - Bottom bore diameter: 53
- Other Features:**
  - Bottom bore diameter: 24^a
  - Bottom bore diameter: 12^a
  - Bottom bore diameter: 44
  - Bottom bore diameter: 43
  - Bottom bore diameter: 48
  - Bottom bore diameter: 53
  - Bottom bore diameter: 10
- Other Labels:**
  - Left side: 1, 4, 5, 6, 7, 21
  - Right side: 3, 35^a, 9^a, 11, 10
  - Bottom: 8^a

UNITED STATES PATENT OFFICE

FRANK L. O. WADSWORTH, OF PITTSBURGH, PENNSYLVANIA

PERCUSSION TOOL

Application filed August 2, 1921. Serial No. 489,189.

My invention relates to improvements in the type of hammer described in my earlier application, Serial No. 369,389, filed March 27, 1920, Patent 1,592,130; and it has to do in part with the method of operation, and in part with the structure and arrangement of the valve elements of pressure-operated-impact tools of this character. The particular features of improvement which form the subject-matter of this application will appear from the following description of two illustrative embodiments of my invention that are respectively depicted in Figs. 1 to 3 and 4 to 6, inclusive, of the accompanying drawings, in which:

Figure 1 is a side elevation—partially in section—of a pneumatic riveting hammer of the long stroke free piston “expansion” type; Figs. 2 and 3 are central longitudinal sections (on an enlarged scale) of the handle end of this same construction showing the distribution valve elements in different successive positions of operations; Fig. 4 is another view, similar to Fig. 1, of another exemplification of my improved construction; and Figs. 5 and 6 are enlarged views (similar to Figs. 2 and 3) showing the distribution valve elements of this second exemplification in successive control positions.

In the construction shown on the first sheet of the drawings, the barrel of the hammer comprises an outer tubular member 1, which is provided at its front end with a sleeve bearing for the reception of a rivet set 2, and which is threaded at its rear end for the attachment of the handle member 3. This barrel carries an inner tubular member 4, which receives and guides the reciprocating piston element 5; and this inner tube is clamped in place between an annular collar 6—that is supported in the front end of the outer tubular member 1—and the end of a cylindrical recess 7 that is formed in the hub of the handle 3. The rear end of the hammer barrel is bored and internally threaded to receive a two-part valve box, which consists of a rear section 8, that is screwed into the barrel, and a front section 9, that engages the outer surface of the inner tubular member 4 and thus maintains the parts 4—8 and 9 in

concentric relation with each other. The space between the exterior of the inner tube 4 and the interengaged concentric valve box sections 8 and 9 constitutes an annular chamber for the reception and guidance of a two-part distribution valve, which consists of a front section 12, that is provided with two flanges 13 and 14, and a rear section 15 that overlaps the front section and is likewise provided with two other flanges 16 and 17. The front end of the rear section 15 is perforated with an annular row of ports 18—18, that are located back of the flange 16; and the central portion of this section is provided with a wide shallow groove 19, which communicates at its rear edge with one or more vents 20 that pierce the valve shell just behind the flange 17. The adjacent portion of the inner tube 4 is provided with two annular rows of ports 21—21 and 22—22, which serve respectively as inlet and exhaust ports for the rear end of the piston chamber—and with an intermediate row of vent openings 23, which open into the groove 19 in the rear valve section. Another row of small ports 24 connect the intermediate part of the piston chamber with the annular chamber 25 in front of the valve flange 13; and the collar 6 (which carries the front end of the tube 4) is provided with a series of radial openings 10 that lead from the front end of the piston chamber into the annular space 11, between the outer tube 1 and the adjacent surfaces of the members 4—6 and 9.

The rear valve box section 8 is provided with a series of longitudinal passageways 26 that connect the conduit 11 with a groove 27 on the inner surface of the valve box; and one or more of these passages 26 are provided with radial ports 28, that communicate with that portion of the chamber 25 in which the valve flange 13 reciprocates. The valve box is also provided with a series of radial passages 29, that open, at their inner ends, into the chamber back of the valve flange 16, and at their outer ends into an annular groove 30 on the inner adjacent surface of the outer tube 1; and the groove 30 communicates in turn with the outer air through an annular row of ports 31—31. A restricted

port 32 leads from the live air reservoir 7, in the hammer handle, to the space back of the rear valve flange 17; and one or more small passages 33 (one of which is shown in full and one in dotted lines in Figs. 2 and 3) lead from this same reservoir 7 to that part of the valve chamber in which the flange 14 reciprocates.

In putting together the parts of the above described construction, the assembled members 4—6—8—9—12 and 15 may be inserted as a unit in the hammer barrel 1; and the rear valve box section 8 is then screwed home until its front end is tightly engaged with the shoulder 34 of the annular recess 30. A compressible washer 35—of soft metal, or fibre, or other suitable material—is slipped over the reduced end portion of the valve box and the handle 3 is screwed onto the exterior of the outer tubular member 1 until the rear end of the inner tube 4 and the washer 35 are both engaged by the adjacent faces of the recess in the handle boss. The handle is then locked in place on the barrel by the use of an eccentric headed pin 36 which engages with ratchet teeth on the end of the threaded handle sleeve—(as shown and described more fully in my copending application Serial No. 483,794, filed July 11, 1921)—and the locking device is covered by a split spring ring 37 which is provided on one side with a series of openings 38, and which serves both as a retaining clip for the locking pin 36 and as an exhaust deflector for the waste motive fluid escaping from the ports 31—31.

The operation of the mechanism shown in Figs. 1 to 3, inclusive, is as follows: When motive fluid is admitted to the reservoir 7 (through the passage 39 in the hammer handle) the piston 5 will be moved, either forward or back, by the flow of the high pressure air through the co-operating passageways and ports in the valve and valve box members. If, for example, the interengaged valve elements 12 and 15 are in the forward position shown in Fig. 1, the live motive fluid will pass directly through the open ports 21 into the rear end of the piston chamber, and will drive the piston 5 toward the rivet set 2. In this position of the valve elements the valve flange 16 is in advance of the groove 27 and there is a direct communication between the latter and the radial openings 29; and the air in front of the advancing piston will therefore be allowed to escape freely to the external atmosphere through the communicating ports and passages 10—11—26—27—29—30—31 and 38. During the first part of the forward movement of the piston member, the small ports 24 are either open to the exhaust or are covered by the piston 5; and the valve elements 12 and 15 are therefore maintained in the position shown in Fig. 1 by the unbalanced pressure of the live motive fluid which acts directly on the exposed rear

end of the valve shell 15 and which is admitted to the chamber back of the valve flange 17 both through the restricted passageway 32, and through the ports and openings 23—19—20. But as soon as the piston, in its forward movement, has passed beyond and uncovered the row of ports 24, the live motive fluid in the rear thereof will enter the chamber 25 and the pressure of this fluid on the valve flange 13, will overcome the pressure on the rear of the flange shell 15 and its flange 17, and the two interengaged valve elements 12 and 15 will be moved rearwardly to the position shown in Fig. 2.

In this second position of the parts the inlet ports 21 are all closed, but a small amount of live motive fluid continues to flow into the rear end of the piston chamber through the restricted passageways 32—20—19 and 23. The communication between the groove 27 and the exhaust ports 29 is now cut off by the valve flange 16; and a communication between the rear end of the piston chamber and the surrounding chamber 11 is established by the opening of the small port or ports 28, which permits a part of the high pressure fluid to flow through the passageways 24—25—28 and 26 into the now closed reservoir 11 and the communicating space in front of the advancing piston. As the forward movement continues the pressure in the rear of the piston—and on the front of the valve flange 13—is continually reduced by the expansion of the trapped motive fluid in the rear of the piston; while the pressure on the front of the piston—which is substantially the same as that in the reservoir 11 and the space between the valve flanges 14 and 16—is continually increased, partly by the compression of the air in front of the advancing piston and partly by the restricted flow of higher pressure air through the ports 28. But the relative sizes of the auxiliary supply ports, 32—23, and the equalizing ports 28,—and the relative volumes of the piston chamber and the segregation chamber 11—are such that the expansion pressure on the rear end of the piston is always substantially greater than the accumulating pressure on the front end, and the impact member is therefore

driven forward at a continually accelerated velocity until it delivers its blow on the rivet set 2 or other operating tool element. And the areas of the valve flanges 13 and 14 are so proportioned that just at, or just prior to, the time of impact, the increasing pressure on the flange 14 will overcome the decreasing pressure on the flange 13, and the front valve section 12 will be moved forward—away from the rear section 15—to the position shown in Fig. 3.

In this third position of the operating elements the communication between the reservoir 11, and the rear end of the piston chamber is shut off—by the movement of the valve

flange 13 over and beyond the equalizing ports 28—and the space behind the piston is opened to the atmosphere by the uncovering of the opposing ports 22—18—29. This permits the expanded motive fluid in the rear end of the piston chamber to escape through the passageways 22—18—29—30—31 and 38; and the piston is now driven rearwardly by the expansion of the trapped fluid in the 5 annular segregation chamber 11. The opening of the rear end of the piston chamber to the exhaust, relieves the pressure on the front valve flange 13, and also on the rear valve flange 17—since the air flowing through the 10 constantly open passage 32 is carried away by the larger passages 20—19—23—and the pressure of the trapped and expanding fluid in the space 11, and between the flanges 14 and 16, is thus enabled to maintain the valve 15 elements in the position shown in Fig. 3 during the major portion of the return stroke of the piston. But when the rearwardly moving member 5 reaches and covers the exhaust ports 22, the further flow of air from the 20 rear end of the piston chamber is stopped; and a slight additional movement of the piston also covers the vents 23, and completely arrests the further escape of air from the back of the valve flange 17. The pressure 25 of the live motive fluid passing through the duct 32 then becomes sufficient to overcome the reduced pressure on the larger valve flange 16, and the rear valve section 15 is thrown forward—thus restoring the parts to 30 the position shown in Fig. 1, in which the exhaust ports 22, and the equalizing ports 28 are both closed, and the admission ports 21 are open—to admit a fresh charge of live 35 motive fluid to the rear of the piston chamber 40 and initiate another cycle of operations.

The action of the operative elements in the third stage of movement—as last described—may be assisted, if desired, by the admission of a limited amount of live motive 45 fluid through the ducts 33—(the inner ends of which are uncovered by the forward movement of the front valve section 12)—to the space between the separated valve flanges 14 and 16, and thence to the annular chamber 11; but this auxiliary supply of live 50 motive fluid to the front end of the piston chamber is not essential to the effective operation of my improved mechanism and may be omitted.

In the second embodiment of my invention, which is shown in Figs. 4, 5 and 6, the general construction and arrangement of the members 1, 2, 3, 4, 5 and 6 are substantially the same as is illustrated in Figs. 1, 2 55 and 3 and do not therefore require further explanation. In the second construction the inner tube 4 is provided with an intermediate casing 40 which is permanently secured thereto, at one or both ends and is spaced 60 therefrom to form an annular passage 41, that leads from the ports 24^a to the front of the annular chamber 25^a, between the inner tube 4 and the two-part valve box 8^a—9^a. The front end of the section 9^a engages 65 closely with the rear end of the casing 40, and is thus held in concentric relation with the inner tube 4; and the two interengaged sections 8^a—9^a are clamped in position between the compressible washers 35^a and 35^b and the adjacent faces of the assembled 70 members 1 and 3, and are also held in fixed angular relation with respect to the outer tube 1 by suitable dowel-pin connections or other equivalent means. The distribution valve, which reciprocates in the annular 75 chamber between the concentric members 4—8^a—9^a consists, as before, of two overlapping but independently movable sections 12^a and 15^a; the first of these sections being provided with an internally turned flange 13^a, 80 and an externally disposed flange 14^a, and the second section being provided with an external flange 16^a and a shoulder 17^a near its rear end. The flange 14^a is provided with a deep groove on its periphery and is pierced 85 with a row of ports 18^a. The adjacent flange 16^a is also grooved and provided with radial ports 42 that open into an annular recess 43, on the inner periphery of the section 15^a; and the front end of this recess is cross connected with an external groove 44 on the same section by the ring of ports 45. The valve box is pierced with longitudinal 90 passages 25 which connect the rear end of the annular chamber 11, with the groove 27; and with inclined passages 29^a that register with corresponding openings 31^a in the wall of the hammer barrel 1; and the outer ends of these last-named ports open into a shallow 95 open groove 30^a at the end of the handle boss. 100 The front valve box section 9^a is further provided with an inclined port 28^a, which leads from that portion of the chamber 25^a that is traversed by the valve flange 13^a, to the reservoir 11; and the opening of this port can 105 be varied, at will, by the adjustable screw plug 46, which is accessible through one of the openings 38 in the spring ring clip 37.

The operation of the last described mechanism is substantially the same as that of the construction shown in Figs. 1, 2 and 3. When the valve mechanism is in the position shown in Fig. 4 the live air admitted through the handle passage and chamber 39—7 passes into the rear end of the piston chamber through 115 the open ports 21. In this position of the valve elements the ports 42 are in registry with the groove 27; the ports 45 and the communicating grooves 43—44 are in communication with the inner ends of the ports 18^a 120 (as best shown in the enlarged view of Fig. 5); and the outer ends of the last mentioned ports open into the inclined exhaust passages 29^a. The air in front of the advancing piston is thus permitted to escape through 125 130

the ports and passages 10, 11—25—27—42—43—45—44—18^a—29^a—31^a—30^a and 38. When the advancing piston passes the ports 24^a the live motive fluid behind it is admitted to the passageway 41 and to the chamber 25^a in front of the valve flange 13^a; and both interengaged valve elements 12—15 are thrown rearwardly to the position shown in Fig. 5. This valve movement simultaneously cuts off communication between the chamber 11 and the outer air (by concurrently moving the ports 42 and 18^a out of registry with the groove 27 and the exhaust openings 29^a) and opens communication between the 10 said chamber and the rear end of the piston chamber (by uncovering the restricted equalizing duct 28^a). The air which is trapped in the rear of the piston—together with a restricted amount of live motive fluid which 20 will flow through the passages 32—20—19 and 23—is expended by the continued forward movement of the piston and by the throttled flow of the expanding fluid through the duct 28^a into the segregating 25 reservoir 11; but this equalizing flow is so restricted as to maintain a higher pressure in the rear of the advancing piston than is exerted on the front end thereof. At the end 30 of the forward stroke, the increasing pressure in the chamber 11 and the passages 25—27, which are now in communication with the space between the valve flanges 14^a and 16^a, overcomes the effect of the diminishing pressure on the front face of the valve flange 35 13^a, and the front section 12^a of the valve member is thrown forward to the position shown in Fig. 6. This movement places the ports 18^a in direct communication with the exhaust openings 22 of the inner tube 4 and 40 also in registry with the diagonal passages 29^a, and thus permits the expanded fluid in the rear end of the piston chamber to escape. But the forward movement of the valve section 12^a closes the port 28^a, and the expansion 45 of the fluid thus trapped in the chamber 11 drives the piston rearwardly until it passes and closes the exhaust ports 22 and the vents 23. When this occurs the leakage of air from the rear side of the valve shoulder 17^a 50 is stopped, and the accumulated pressure of the live motive fluid which flows in through the duct 32 overcomes the reduced pressure of the expanded air in the chamber 11 and passageways 25—27 (which acts on the front 55 face of the flange 16^a) and the rear section 15^a is thrown forward. This restores the parts to the position shown in Fig. 1 and the previously described cycle of movements is repeated.

60 When the valve elements are separated—as shown in Fig. 6—the grooved recess in the periphery of the valve flange 16^a is brought in registry with the inner end of the restricted passageway 33; and the rear edge of the 65 groove 44 is uncovered; and a small amount

of live motive fluid is thus allowed to flow from the handle reservoir 7 to the space between the valve flanges 14^a and 16^a, and thence, through the passages 27—25, to the segregation chamber 11. This auxiliary supply of high pressure air assists in the maintenance of the valve elements in the position shown in Fig. 6, and also in the return of the piston to the rear end of its chamber; but it is not essential to the proper and effective 70 operation of the mechanism and may be dispensed with if the areas of the various other supply passages, and the relative volumes of the piston and the segregation chambers, are properly proportioned. 75

It will be readily understood that the degree of expansion of each live air charge—during the impact stroke of the piston—may be controlled by varying the position of the control ports 24; and that the ratio between the pressures on the two ends of the piston at the end of the impact stroke (i. e., the pressures in the piston chamber and the chamber 11) may be varied and controlled by the size of the equalizing throttle ports, 28 or 28^a. It will also be understood that the degree of expansion of the segregated charge, which is trapped in the chamber 11 by the separation of the valve elements (Figs. 3 or 6), is determined by the ratio between the volumes of the piston chamber, and the said segregation chamber; and that the volume of the latter may be varied to any required degree by altering the thickness of the inner tube 4, or of the portion of it which is between the 90 collar 6 and the front valve box section. 95

It will also be apparent to those skilled in this art that my improved type of "multiple expansion hammer" can be operated with a much smaller amount of compressed air (or 105 other motive fluid) than is necessary to run a pneumatic tool of the ordinary type in which the forward and the return strokes of the piston are effected by separate and successive 110 charges of live motive fluid, which are admitted, and act at substantially constant pressure, during the entire length of travel of the reciprocating member. Another important advantage of the mode of operation herein described is that the return stroke of the piston is more promptly initiated by the action 115 of the segregated charge in the chamber 11, than it can be by a charge of fresh motive fluid that is admitted at the opposite end of the hammer; and the speed of operation is thereby increased. This last feature of advantage is accentuated and amplified by the positioning of the admission ports 21 at the extreme rear end of the piston chamber, and the opening of these ports (by the actuation 125 of the individual valve element 15 or 15^a) before the piston has reached and covered them on its backward stroke. The reversal of the return movement, and the initiation of the forward stroke is thus accelerated, and a fur- 130

ther increase in the average speed of reciprocation—(i. e., in the aggregate number of strokes per unit of time)—is attained.

My improved hammer construction also 5 presents various features of structural advantage—such as the complete protection of the distribution valve elements against any wear, or other injury, produced by the vibration of the moving piston; the ready accessibility of all the operating parts; and the easy renewal and replacement of the inner piston guide tube—all of which will be appreciated by those familiar with the practical construction and manipulation of this class 10 of tools; and engineers and artisans having such familiarity will, with the preceding disclosure as a guide, be able to utilize my improvements—in whole or in part as may be desired—in various other forms of pressure- 15 actuated impact tools, such as chipping hammers, air drills, sand ramers and the like, which are not herein specifically illustrated.

What I claim is:

1. In combination in a fluid-driven impact tool, a cylinder, a piston operating therein, a valve mechanism comprising two independently movable sections, means for actuating one of said sections to admit motive fluid behind the piston and move it forwardly, 20 means for actuating both sections conjointly for cutting off the supply of motive fluid during said forward stroke, and means for actuating the other of said sections to trap motive fluid in front of the piston and move it rear- 25 wardly.

2. In a fluid-actuated percussion tool, the combination of a cylinder, a piston reciprocable therein, a segregation chamber, a distribution valve comprising two independently 30 movable sections, each responsive to variations in fluid pressure in the tool, means for actuating one of said sections to admit motive fluid behind the piston and drive it forwardly, other means for actuating both sections 35 conjointly at an intermediate point in said forward movement, and further means for actuating the other of said valve sections at the completion of said forward movement of the piston.

3. In a fluid-actuated percussion tool, the combination of a piston chamber, a piston reciprocable therein, a segregation chamber, a distribution valve mechanism comprising a plurality of independently movable sections, 40 means for actuating one of these sections to admit fluid to the rear end of the piston chamber, means for actuating the valve mechanism as a whole to simultaneously cut off the admission of fluid to the rear end of the piston 45 chamber and the escape of fluid from the segregation chamber, and other means for independently moving another of said valve sections to open the rear end of the piston chamber to the exhaust.

4. A pneumatic hammer, including a pis-

ton, a cylinder in which the piston operates, a reservoir and a two part valve, said parts of the valve moving conjointly to cut off the delivery of fluid to said cylinder and to deliver fluid to said reservoir, and moving independently to cut off delivery of fluid to said reservoir, and to deliver fluid to said cylinder. 70

5. A pneumatic hammer, including a piston chamber, a reservoir, a piston operating in the chamber, and a two part valve in which one part moves independently to deliver fluid to the cylinder and to close the exhaust ports thereof, and the other part moves independently to open the exhaust ports of said cylinder and to close the exhaust from said reservoir, and moves with the first mentioned part to deliver fluid to said reservoir while said first mentioned part is moving to cut off the admission of fluid to said cylinder. 75

6. A pneumatic hammer, including a piston chamber, a reservoir, a piston operating in the chamber and a two part valve in which the parts are adapted to move independently in controlling the delivery of fluid to the cylinder and to cut off communication between the cylinder and the reservoir, and in which they move together in concurrently cutting off the delivery of fluid to the cylinder, and in establishing communication between the cylinder and the reservoir. 80

7. In combination in a fluid actuated impact tool, a casing, enclosing a segregation chamber and a cylinder having inlet and exhaust ports located at the rear end thereof and communicating at its forward end with said chamber, a piston operating in said cylinder, means for closing said inlet ports while said piston is moving forward in response to pressure of fluid delivered therethrough, and means operative after said first mentioned means to trap partially expanded fluid from said cylinder in said chamber and to simultaneously open said exhaust ports. 95

8. In a fluid actuated percussion tool, the combination of a cylinder enclosing a piston chamber and a segregation chamber, a piston operating within said piston chamber, a distributing valve surrounding and concentric with said piston chamber and comprising two independently movable overlapping concentric sections, each responsive to variations of pressure within both of said chambers, and a flange on one of said sections subjected to pressure from one of said chambers for moving such section to cut off the supply of motive fluid behind said piston chamber before said piston has moved through the major portion of its forward stroke, and a flange on the other section subjected to pressure from one of said chambers for trapping fluid 100

in said segregation chamber and opening said piston chamber to the atmosphere. 105

9. In combination in a fluid actuated tool, a casing enclosing a chamber, and a cylinder having inlet and exhaust ports at the rear 110

130

end thereof, said chamber and said cylinder being in open communication at the forward end thereof, a piston operating in said cylinder, means for closing said inlet ports while said piston is moving forward through said cylinder in response to the pressure of fluid delivered therethrough, and means operative after said first mentioned means for trapping partially expanded motive fluid in said chamber to return said piston and for opening said exhaust ports.

10. In combination in a fluid actuated tool, a casing enclosing a chamber and a cylinder having inlet and exhaust ports formed in the rear end thereof, said cylinder and chamber being in open communication at the forward end of said cylinder, a piston operating in said cylinder, means movable in response to fluid pressure within said tool for closing said inlet ports and communication between said chamber and the atmosphere while said piston is moving in response to fluid pressure admitted through said inlet ports, and means operative after said first mentioned means 20 for trapping partially expanded motive fluid from said cylinder in said chamber and for opening said exhaust ports.

11. In combination in a fluid actuated tool, a casing enclosing a chamber and a cylinder having inlet and exhaust ports at the rear end thereof and in open communication with said chamber at the forward end thereof, a free piston operating within said cylinder, a valve mechanism at the rear end of said cylinder for closing said inlet ports while said piston is moving in response to fluid pressure delivered therethrough, and for subsequently opening said exhaust ports and trapping partially expanded fluid from said cylinder in said chamber to return said piston.

12. In combination in a fluid actuated percussion tool, a casing enclosing a working cylinder having inlet and exhaust ports for motive fluid, and a segregation chamber communicating with the forward end of said cylinder, a free piston located within said cylinder, means responsive to variations of fluid pressure within said tool for cutting off the delivery of motive fluid through said inlet ports before said piston reaches the end of its working stroke, and means operative after said first mentioned means to trap fluid from said cylinder in said chamber and to open said exhaust ports whereby said piston is returned to its initial position by the fluid trapped in said chamber.

13. In a percussion tool, a cylinder having inlet and exhaust ports for motive fluid, a segregation chamber communicating with the forward end of said cylinder, and having an exhaust passage, a free piston reciprocatable within said cylinder, means for controlling the delivery of motive fluid to said cylinder through said inlet port, to move said piston in a forward direction, and to

open the exhaust passage of said chamber, and means for trapping partially expanded motive fluid from said cylinder in said chamber and for simultaneously opening the exhaust ports of said cylinder to permit the 70 trapped fluid to move said piston in a rearward direction in said cylinder.

14. In combination in a fluid impact tool, a casing enclosing a segregation chamber, and a cylinder having inlet and exhaust ports for motive fluid and having its forward end in continuous communication with said chamber, a free piston operating within said cylinder, means for closing the inlet port of said cylinder and simultaneously shutting off 75 communication between said chamber and the atmosphere while said piston is moving forwardly in response to the pressure of motive fluid delivered through said inlet ports, and means operative after said first mentioned means to trap partially expanded fluid from said cylinder in said chamber and for simultaneously opening the exhaust ports of said cylinder.

15. In a fluid actuated impact tool, a casing enclosing a cylinder having inlet and exhaust ports for motive fluid, and a segregation chamber in open communication with the forward end of said cylinder and having an exhaust port, a valve mechanism responsive in operation to variations of the pressure of the motive fluid within the working passages of said tool, for simultaneously opening the inlet port of said cylinder and the exhaust port of said chamber, to drive said piston forward, means for admitting fluid to said segregation chamber from said cylinder, and for subsequently trapping partially expanded motive fluid from said cylinder in said chamber and simultaneously opening the 90 exhaust port of said cylinder to drive the piston in the opposite direction.

16. In a fluid actuated percussion tool, the combination of a casing enclosing a cylinder having inlet and exhaust ports for motive fluid, and a segregation chamber having an exhaust port and communicating at its forward end with said cylinder, a free piston operating within said cylinder, and a valve mechanism comprising two independently movable sections, one for controlling the delivery of motive fluid through the inlet port of said cylinder and the exhaust port of said chamber and the other for controlling the delivery of motive fluid through the exhaust port of said cylinder and communication between the rearward end of said cylinder and said chamber, and both responsive in operation to variations in fluid pressure within 105 said casing.

In testimony whereof, I have hereunto subscribed my name this 28th day of July, 1921.

FRANK L. O. WADSWORTH.
